UNITED STATES PATENT OFFICE.

JAMES B. SMITH, OF NEW YORK, N. Y., ASSIGNOR TO THE STANDARD PENCIL COMPANY, OF SAME PLACE.

GLOVE OR SHOE BUTTONER.

SPECIFICATION forming part of Letters Patent No. 368,024, dated August 9, 1887.

Application filed March 3, 1887. Serial No. 229,572. (No model.)

To all whom it may concern:

Be it known that I, JAMES B. SMITH, a citizen of the United States, residing at New York, county and State of New York, have 5 invented a new and useful Improvement in Pocket Glove or Shoe Buttoners, of which the following, taken in connection with the accompanying drawings, is a full and complete specification.

10 The object of my invention is to provide a neat, convenient, and compact pocket glove or shoe buttoner.

My invention consists in combining a closed wire loop glove or shoe buttoner of the form 15 shown with a cylindrical case open at the ends only, into which it can be slid when not in use. A solid head is secured to the end of the case, and this is provided with notches through which the wire sides of the buttoning-loop 20 pass, and these notches also serve the purpose of strengthening and steadyng the loop when in use. The case may contain a sliding pencil, as shown.

In the drawings, Figure 1 is a view of the 25 device with both pencil and glove-buttoner slid into the case. Fig. 2 is a similar view with the buttoning-hook fully withdrawn and the pencil partly withdrawn. Fig. 3 is a rear end view of the cylindrical body of the case. 30 Figs. 4 and 5 are views of opposite sides of the buttoning-loop when removed from the case. Fig. 6 is a view of the inner body portion. Fig. 7 is a view of the buttoner closed when constructed without the pencil.

35 *a* is a plain thin tubular case flanged over inwardly at the rear end and provided with the diametrically-opposite notches *a'* *a'*.

b is a globular cap having grooves upon opposite sides. One of these grooves is shown at 40 *f*, Fig. 6. To *b* is soldered a tube, *b'*, in which a spiral slot, *h*, is cut. A pin, *i*, set in the lead-holder *l*, works in this slot *h*, and also in a longitudinal slot in the smaller tube, *m*, which

turns inside of *b'*, and itself contains the lead-holder. The further description of these parts 45 is, however, unnecessary, as they are the same as those usually employed in the construction of propelling-pencils.

c is a tip.

d is the button hook or, more properly, 50 loop, to which is soldered at the open end a slotted hollow cylindrical piece, *e*, of such diameter as to closely fit the inside of the outer case. This has a slot, *e'*, extending completely through it, and one or more slips or 55 saw-cuts, *e''*, to render it more elastic. The metal of this cylindrical end is thin enough to permit it to slide freely over the parts of the propelling-pencil, and yet it has sufficient elasticity to hold it in any position, either in or 60 out, and to make the sliding motion smooth and steady.

I am aware that combinations of a button-hook and a pencil have been made, that button-hooks sliding into a case have been in use, 65 and that even the combination of a loop glove-buttoner with a pocket propelling-pencil in which the wire forming the loop slid into the cylindrical case by slots in that case has been in use, and I therefore do not claim, broadly, 70 the combination of a propelling-pencil with an adjustable buttoner; but

What I do claim, and desire to secure by Letters Patent, is—

The combination of the cylindrical case *a*, 75 open at the end and provided with the notched head *b* and the notches *a'*, and the elastic wire loop *d*, of the form shown and having the cylindrical end *e*, all constructed and operating substantially as shown.

In witness whereof I have hereunto set my hand this 28th day of February, 1887.

JAMES B. SMITH.

Witnesses:

W. C. MAINLAND,
GEO. H. SONNEBORN.
